Patented Dec. 23, 1975

238,156

SONIC SIGNAL GENERATOR WITH SOUND LIMITER

David L. Livermore, Seattle, Wash., assignor to Proctor & Associates Company, Redmond, Wash.

Filed Dec. 12, 1973, Ser. No. 424,164

Term of patent 14 years

Int. Cl. D10—06

U.S. Cl. D10—116

Fig. 1.

Fig. 2.

Fig. 3.

Fig. 4.

Fig. 6.

Fig. 5.

Fig. 7.

FIG. 1 is a perspective view of the sonic signal generator with sound limiter showing my new design;

FIG. 2 is a front elevational view;

FIG. 3 is a left side elevational view;

FIG. 4 is a top plan view;

FIG. 5 is a rear elevational view;

FIG. 6 is a right side elevational view;

FIG. 7 is a bottom plan view.

I claim:

The ornamental design for a sonic signal generator with sound limiter, as shown.
